Attorney

UNITED STATES PATENT OFFICE

DION ATTIS WHITE, OF FORREST HILLS, COVINGTON, KENTUCKY

STEPLADDER, PRESSING BOARD, AND TABLE COMBINED

Application filed July 2, 1928. Serial No. 289,879.

This invention relates to a combination stepladder, pressing board and table, and it is an object of the invention to provide a device of this kind wherein the pressing board 5 serves as a support when the device is employed as a stepladder and wherein the stepladder is constructed in a manner to provide a rigid support when the device is used as a pressing board or table.

10 The invention consists in the details of construction and in the combination and arrangement of the several parts of my improved combination stepladder, pressing board and table whereby certain important 15 advantages are attained and the device rendered simpler, less expensive and otherwise more convenient and advantageous for use, as will be hereinafter more fully set forth.

The novel features of my invention will 20 hereinafter be definitely claimed.

In order that my invention may be the better understood, I will now proceed to describe the same with reference to the accompanying drawings, wherein:

25 Figure 1 is a view partly in side elevation and partly in section illustrating a device constructed in accordance with an embodiment of my invention adjusted for use as a stepladder;

30 Figure 2 is a view in front elevation of the device as illustrated in Figure 1;

Figure 3 is a view partly in section and partly in elevation of the device adjusted for use as a pressing board;

35 Figure 4 is a detailed sectional view taken substantially on the line 4—4 of Figure 1;

Figure 5 is a detailed sectional view taken substantially on the line 5—5 of Figure 1;

40 Figure 6 is a detailed sectional view taken substantially on the line 6—6 of Figure 1;

Figure 7 is a detailed sectional view taken substantially on the line 7—7 of Figure 1; and

45 Figure 8 is a view in bottom plan of the board with the associated leaves to permit the device to be employed as a table.

As disclosed in the drawings, 1, 2, 3 and 4 denote steps comprised in the ladder structure and which are associated with the side 50 rails 6 and 7. The supplemental or addi-

tional rails 7 are adapted to be folded and adjusted inwardly of the rails 6 and to be disposed lengthwise thereof when said rails 6 and 7 are compacted.

The top step 1 is provided at its opposite 55 ends and closely adjacent to its forward margin with the upstanding spindles or trunnions 18 engageable within suitable openings provided in the side rails 6 whereby said step 1 is supported for swinging movement. 60

The rear marginal portion of the step 1 is operatively connected by a bracket 15 with an end portion of a presser board 5 thereby providing means whereby the board 5, as particularly illustrated in Figure 1, can be used 65 as a supporting member or back leg for the device when employed as a stepladder. The opposite end portions of the rails 6 are connected by a cross rod or brace 9.

The second step 2 has each end portion received within a transversely disposed channel 20 provided in the rails 6 and each end portion of said step 2 is provided with a spindle or trunnion extending through a suitable opening in communication with said channel 75 20.

The inner rails 7 at the upper end portions thereof are connected or tied by a brace 8 and the rails 7 substantially midway their ends are provided with transversely disposed 80 grooves or channels 20 in each of which is received a marginal portion of the third step 3. Each end portion of this step 3 is provided with an outstanding spindle or trunnion disposed through a rail 7 and the adjacent rail 6 whereby said rails 6 and 7 are connected for relative swinging movement. The remaining step 4 is carried by and interposed between the lower portions of the rails 7. 85

The forward end portions of the rails 6 at the upper parts thereof are provided with notches or recesses 16 to receive the rear portion of the step 2 when said rails 6 and 7 are in folded or compacted relation, each of said recesses 16 being of a formation to readily permit desired relative swinging movement of said rails. 95

With the parts as illustrated in Figure 1 adjusted to permit the device to be used as a 100

stepladder, an elongated rigid brace 12 is hingedly connected, as at 11, to the inner or under face of the board, such connection being of a detachable type. The opposite end portion of this brace carries a hook for engagement with an eye member 14 extending rearwardly from the step 3 whereby the board 5 is effectively maintained in desired position to serve as a support or back leg for the structure.

In Figure 3 of the drawings, the device is shown as adjusted for use as a pressing board with the rails 6 and 7 swung or adjusted into crossed relation. The lower or free end portions of the rails 6 are arranged for contact with any desired supporting surface while the upper end portions of the legs 7 are in contact with a butting member 10 disposed transversely across the under surface of the board 5.

In Figure 8 a detachable leaf 28 is shown disposed along each side of the board 5 to permit the device to be employed as a table. Each leaf 28 is connected by hinges 11 to the marginal portions of the board 5, said hinges being readily separated so that the leaves 28 may be applied or removed as desired. The leaves 28 when raised facilitate the use of the device as a table supported by the braces 22 secured to the under surface of the board 5 at points desired. The braces 22 when swung outwardly underlie the raised leaves 28 and each of the braces 22 is pivotally connected with a plate 23 through the medium of a conventional bolt 24 and nut 25. The wedges 26 are carried by the board 5 for coaction with the braces 22 to tighten the same.

The outer or free end portion of the board 5 has secured to the under surface thereof a hanger 27 through which the brace 12 is adapted to be disposed to provide further support for the leaves 28.

From the foregoing description it is thought to be obvious that a combination stepladder, pressing board and table constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A combined stepladder and pressing board comprising side rails, a step interposed between and pivotally engaged with the upper portions of said rails, supplemental rails adapted to be disposed inwardly of the first named rails closely adjacent thereto, a

step interposed between the second named rails and having spindles extending through the adjacent portions of all the rails whereby the first named rails and second named rails are capable of relative swinging movement, a step interposed between the second named rails and carried thereby and positioned below the second named step, a pressing board, means for connecting an end portion of said board to the first named step, a brace member, means for connecting an extremity of said brace member to the board, and coacting means carried by the brace member and second step for detachably connecting the brace member with said step.

2. A combined stepladder and pressing board comprising side rails, a step interposed between and pivotally engaged with the upper portions of said rails, supplemental rails adapted to be disposed inwardly of the first named rails closely adjacent thereto, a step interposed between the second named rails and having spindles extending through the adjacent portions of all the rails whereby the first named rails and second named rails are capable of relative swinging movement, a step interposed between the second named rails and carried thereby and positioned below the second named step, a pressing board, means for connecting an end portion of said board to the first named step, leaves, coacting means carried by the board and leaves for detachably connecting said leaves and board, and means carried by the board for coaction with the leaves to maintain the leaves raised.

DION ATTIS WHITE.
